UNITED STATES PATENT OFFICE.

CHARLES B. WEBB, OF PHILADELPHIA, PENNSYLVANIA.

MACHINE FOR CUTTING SHANK-STIFFENERS FOR BOOTS AND SHOES.

SPECIFICATION forming part of Letters Patent No. 252,281, dated January 10, 1882.
Application filed November 28, 1881. (No model.)

To all whom it may concern:

Be it known that I, CHARLES B. WEBB, a citizen of the United States, residing in Philadelphia, Pennsylvania, have invented a Machine for Cutting Shank-Stiffeners for Boots and Shoes, of which the following is a specification.

The object of my invention is to rapidly and accurately cut from pieces of leather beveled strips available for use as shank-stiffeners for boots and shoes; and this object I attain in the manner which I will now proceed to describe, reference being had to the accompanying drawings, in which—

15 Figure 1 is a front view of a machine for carrying out my invention; Fig. 2, a section on the line 1 2; Fig. 3, a perspective view of the cutting-knife, and Fig. 4 a diagram illustrating the operation of the machine.

20 A is the frame of the machine, having bearings for a shaft, B, which carries a fluted or serrated feed-roll, D, and is furnished with two spur-wheels, a and b, the former gearing into a pinion, d, on the short driving-shaft E, and the spur-wheel b gearing into a pinion, e, 25 on a shaft, F, which is adapted to bearings in a sliding frame, G, and carries a feed-roll, J, also serrated. The frame G is acted upon by a spring, f, which tends to force the said frame upward, but permits it to yield to accommodate different thicknesses of leather introduced between the rolls D and J, the frame being guided in its movements by rods i, adapted to openings in a projection, m, of the frame A, 30 and provided with nuts n, which by contact with said projection limit the upward movement of the frame G and its roll J.

M is the cutting-knife, the front or cutting edge of which is beveled on the under side, 35 the continuity of the beveled edge x being interrupted by the formation at the center of the knife of a gouge, y, beveled in the opposite direction from the edge x. When the upper edge of the knife is directly in line with the lower edge of the feed-roll D and a piece of leather is forced against the knife by the feed-rolls, the gouge y will cut from the upper surface of said piece of leather a strip of a shape corresponding with that of said gouge, the portions of the piece of leather on each side of the gouge being deflected downward by the beveled edge x of the knife, as shown in the diagram, Fig. 4.

It is important that the upper edge of the knife M should be in line with the lower edge 55 of the upper feed-roll; otherwise there will be on each side of the cut strip a fin of leather, which must be afterward removed. I therefore attach the knife M to a frame, N, which is secured to a bar, P, at the back of the machine, so as to be capable of vertical adjustment in respect to said bar. The knife itself is adjustable from and toward the rolls, the bolts whereby the knife is secured to the frame N being adapted to longitudinal slots in said 60 knife.

By the above-described machine I am enabled to cut with great rapidity from waste pieces or scraps of leather strips suitable for the shank-stiffeners of boots and shoes, said 70 strips being much more accurate than those cut by hand in the usual way.

Any desired shape may be imparted to the gouge y, and, if desired, said gouge may form part of a strip separate from the rest of the knife 75 and removable from or adjustable in respect to the same. The making of the knife in one piece is, however, preferred.

I claim as my invention—

1. The within-described knife for cutting 80 shank-stiffeners, said knife having a beveled front edge, x, the continuity of which is interrupted by the gouge y, beveled in the opposite direction, as set forth.

2. A knife for cutting shank-stiffeners, said 85 knife having a cutting-edge, part of which is beveled on one side and the remaining part made in the shape of a gouge and beveled on the opposite side, the whole being made in one piece, as set forth.

3. The combination of the knife M, having 90 the beveled edge x, and gouge y, with the feed-rolls D and J, as set forth.

4. The combination of the feed-rolls D and 95 J, the knife M, having a beveled edge, x, and gouge y, and the knife-carrier N, vertically adjustable on the frame of the machine, as set forth.

In testimony whereof I have signed my name to this specification in the presence of two subscribing witnesses.

CHAS. B. WEBB.
